DESIGN FOR A SNOWSHIELD OR THE LIKE

Rene Hubert, Hollywood, Calif.

Application November 15, 1941, Serial No. 104,168

Term of patent 3½ years

To all whom it may concern:

Be it known that I, Rene Hubert, a citizen of Switzerland and resident of Hollywood, in the county of Los Angeles and State of California, have invented a new, original, and ornamental Design for a Snowshield or the like, of which the following is a specification, reference being had to the accompanying drawing, forming part hereof, in which:

Fig. 2 is a front elevational view thereof; and
Fig. 3 is a top plan view.

I claim:

The ornamental design for a snowshield or the like, substantially as shown.

RENE HUBERT.
